SHOE SUPPORT

Andrew Eppler, Lynn, Mass., assignor to United
Shoe Machinery Corporation, Paterson, N. J., a
corporation of New Jersey

Application August 11, 1932, Serial No. 628,354

9 Claims. (Cl. 12—127)

This invention relates to shoe supports, the term "shoe" being generally used herein with reference to a shoe mounted on a last. The invention is herein illustrated as embodied in a shoe support that is part of a machine for leveling the bottoms of shoes progressively, but it is to be understood that it is not thus limited in its applicability.

A feature of the invention consists in novel means for supporting a shoe at the top of the forepart, so constructed as to adjust itself readily to the contour of each shoe and thus to insure that each shoe will be effectively supported against pressure applied on its bottom face without danger of damage to the upper through excessive pressure of the supporting means thereon in any location. For the purpose in view the construction shown comprises a forepart-supporting device or toe rest movable about an axis 20 extending laterally of the shoe and located substantially at its shoe-engaging face to minimize any tendency for the device to rub on the upper in its adjustment to the contour of the shoe, the device being supported on roller bearings to 25 permit it to adjust itself readily to the shoe in response to pressure of the shoe thereon. Combined with this forepart-supporting device, in the construction herein shown, is a heel-end support comprising a member so mounted as to adjust 30 itself readily to the top face of the cone of the last to assist in insuring against breakage of the last when heavy pressure is applied on the shoe bottom; but it is to be understood that in its more general aspects the invention is not limited to this particular combination.

The novel features of the invention will now be more particularly described by reference to the accompanying drawing and pointed out in the claims.

40 In the drawing,

Fig. 1 is a view in side elevation of a portion of a machine in which the invention is embodied, parts being broken away to illustrate the construction more clearly;

45 Fig. 2 is a section on the line II—II of Fig. 1; and

Fig. 3 is a section on the line III—III of Fig. 1.

The invention is herein illustrated as applied 50 to a leveling machine of a well-known type, characteristic features of which are illustrated and described in various prior United States Letters Patent, including Letters Patent No. 1,667,761, granted on May 1, 1928 upon an application of E. E. Winkley and H. A. Davenport. Such ma-

chines include in their organization a shoe support or jack comprising a heel post 10 and a toe post 12 carrying means whereby the shoe and last are supported for the leveling operation performed by a roll 13 that applies downward pressure on the sole and acts progressively along the shoe bottom as the jack is swung in directions lengthwise of the shoe. The heel post 10 carries a spindle 14 which enters the spindle hole in the heel end of the last, the spindle being mounted 60 on a block 16 pivoted at 18 on an upward extension of the heel post to swing in directions lengthwise of the shoe. The block 16 is connected by a link 20 to mechanism (not shown) whereby the block and spindle may be swung to 65 press the toe end of the shoe firmly down upon toe-supporting means on the toe post 12, as more fully disclosed in Letters Patent No. 1,719,158, granted on July 2, 1929 upon an application of E. E. Winkley and H. A. Davenport. This toe- 70 supporting means is in many respects similar to the disclosure of Letters Patent No. 1,171,383, granted on February 8, 1916 upon an application of W. C. Baxter, and comprises a member 22 adjustable on arcuate guideways on the toe post 75 12 by means of a worm 24, this member having mounted thereon a block 26 adjustable upwardly or downwardly by means of a wedge 28. Supported on the block 26 is a toe-supporting device 80 or toe rest 30 comprising a rubber pad 32 hollowed 85 out to receive the toe of the shoe and a holder 34 on which the pad is mounted.

For purposes of this invention the toe rest 30 in the construction shown is so mounted on the block 26 as to permit it to adjust itself to each 90 shoe about an axis extending laterally of the shoe and located substantially at the shoe-engaging face of the pad 32. To this end, the block 26 has an upper face 36 curved about such an axis to provide an arcuate guideway, and the holder 95 34 has a similarly curved lower face 38 which rests upon roller bearings supported on the face 36. The roller bearings comprise rolls 40 mounted at their ends in curved plates 42 which hold them in assembled relation and move with them 100 along the guideway 36. The holder 34 has laterally projecting flanges 44 which are overlapped by flanges formed on retaining plates 46 that are fastened to the block 26. By this means the toe rest 30 is held in place on the roller bearings 105 while permitted to turn freely about an axis located substantially at the upper-engaging face of the pad 32 to adjust itself to each shoe without any substantial displacement of its upper-engag- 110 ing face lengthwise of the shoe and therefore

without any substantial rubbing action on the upper. An effective support is thus provided for the toe end of the shoe over an extended area without danger of excessive pressure on the upper 5 in any location, the pressure being substantially uniform on all portions of the upper engaged by the pad 32. To limit the movement of the toe rest in one direction when there is no shoe in the machine there is provided on one of the plates 10 46 a screw 48 the inner end of which is arranged to engage a shoulder 50 on one of the flanges 44.

Further to assist in supporting the shoe and last firmly against pressure applied on the bottom of the shoe, there is mounted on the block 15 16 for engagement with the top face of the cone of the last a plate 52 provided at its opposite sides with downturned flanges 54 having arcuate lower edges supported on similarly curved shoulders of the block 16, the plate being provided 20 with an opening 56 considerably larger than the spindle 14 and through which the spindle extends. The plate 52 is accordingly free to tip about an axis extending laterally of the shoe to adjust itself to the top face of each last and thus 25 to provide a firm support for the last both forwardly and rearwardly of the spindle, this axis, as shown, being located substantially at the top of the cone of the last. To retain the plate 52 in proper position its flanges 54 are provided with 30 pins 58 which extend into curved slots 60 in portions of the block 16 that are adjacent to the flanges.

While there are herein disclosed, as above described, supporting devices that are self adjusting at both the toe and heel ends of the last and shoe, it will be understood, as hereinbefore suggested, that the invention is not limited to such devices in combination; nor is it limited to a forepart-supporting device movable about 40 an axis located precisely as described. It is also to be understood that the invention is generally applicable to machines for performing various operations on shoes.

Having described my invention, what I claim as 45 new and desire to secure by Letters Patent of the United States is:—

1. In a shoe support, a device for supporting a shoe at the top of the forepart, and curved guiding means on which said device is mounted 50 for adjustment to each shoe about an axis extending laterally of the shoe in response to pressure of the shoe thereon, said axis being located in such proximity to the shoe-engaging face of the device as to avoid any substantial rubbing action of the device on the shoe in its adjusting movement.

2. In a shoe support, a device for supporting a shoe at the top of the forepart, and bearing means supporting said device for self-adjustment 60 to each shoe about an axis extending laterally of the shoe and located substantially at its shoe-engaging face.

3. In a shoe support, a device for supporting a shoe at the top of the forepart, said device comprising a shoe-engaging pad and a holder for said pad, and bearing means supporting said holder

for self-adjustment to each shoe about an axis extending laterally of the shoe and located substantially at the shoe-engaging face of the pad.

4. In a shoe support, a device for supporting a shoe at the top of the forepart, said device being movable about an axis extending laterally of the shoe and located substantially at its shoe-engaging face, and rotatable bearing members supporting the device and relatively to which it is movable about said axis in response to pressure of the shoe thereon to permit the device to adjust itself to the shoe. 80

5. In a shoe support, a device for supporting a shoe at the top of the forepart, said device comprising a shoe-engaging pad and a holder for said pad movable about an axis extending laterally of the shoe and so located as to avoid any substantial rubbing action of the pad on the shoe by movement of the holder, and rotatable bearing members supporting said holder and relatively to which it is movable about said axis in response to pressure of the shoe on the pad to permit the device to adjust itself to the shoe. 90

6. In a shoe support, a device for supporting a shoe at the top of the forepart, a member supporting said device and provided with an arcuate guideway curved about an axis extending laterally of the shoe, and roller bearings on said guideway on which the device is mounted for movement about said axis in response to pressure 105 of the shoe thereon.

7. In a shoe support, a device for supporting a shoe at the top of the forepart, said device comprising a shoe-engaging pad and a holder for said pad having a lower face curved about an axis extending laterally of the shoe and located substantially at the shoe-engaging face of the pad, a member having a similarly curved upper face for supporting said holder, and roller bearings between said faces to facilitate movement of the device about its axis in response to pressure of the shoe thereon. 110

8. In a shoe support, a device for supporting a shoe at the top of the forepart, rotatable bearing members supporting said device for movement about an axis extending laterally of the shoe in response to pressure of the shoe thereon to permit the device to adjust itself to the shoe, the device being provided with flanges at its opposite sides, and means for engaging said flanges 125 to retain the device on the bearing members.

9. In a shoe support, means for supporting a shoe and last both at the forepart and at the heel end, said supporting means comprising devices arranged respectively to engage the shoe 130 at the top of the forepart and to engage the top of the cone of the last and each mounted for movement about an axis extending laterally of the shoe in response to pressure of the shoe or last thereon to adjust itself to the contour of the 135 shoe or last, the axes of movement of said devices being located substantially at the top of the forepart of the shoe and at the top of the cone of the last respectively.

ANDREW EPPLER. 140
